UNITED STATES PATENT OFFICE.

HARMON F. DAVENPORT, OF CHICAGO, ILLINOIS, ASSIGNOR TO THE BRUNSWICK-BALKE-COLLENDER CO., OF CHICAGO, ILLINOIS, A CORPORATION OF DELAWARE.

DESIGN FOR A CUE-RACK.

42,353.

Specification for Design.

Patented Mar. 26, 1912.

Application filed July 1, 1911. Serial No. 636,549. Term of patent 14 years.

To all whom it may concern:

Be it known that I, HARMON F. DAVENPORT, a citizen of the United States, residing at Chicago, in the county of Cook and State of Illinois, have invented a new, original, and ornamental Design for Cue-Racks, of which the following is a specification, reference being had to the accompanying drawing, forming a part thereof.

Figure 1 is a front elevation of a cue rack

showing my design; Fig. 2 is a plan view; and Fig. 3 is a side elevation thereof.

I claim:

The ornamental design for a cue rack, as shown.

HARMON F. DAVENPORT.

Witnesses:

M. L. CRUSE,

G. E. HOLMES.
